CONVEYER AND CUTTING MECHANISM FOR WRAPPING MACHINES

Benjamin Redmond, New York, N. Y., assignor to Chiplets Incorporated, New York, N. Y., a corporation of New York

Application April 12, 1946, Serial No. 661,697

14 Claims. (Cl. 164—42)

1
This invention relates to a mechanism useful in a machine for wrapping a commodity, product of manufacture or other articles of merchandise, and advantageously useful for wrapping butter.

The principal object of the invention is the provision of a mechanism which is designed and adapted to utilize wrapping material as a means for conveying the butter in slabs from a feeding means to a wrapping means along a path enabling printing and cutting of the slabs into patties or chiplets by means suitably arranged adjacent the path traversed by the wrapping material; and the material to be cut by means adjacent said path into individual wrappers for the printed and cut butter.

With the foregoing and other objects in view the invention resides in the combination, construction and operation of the parts hereinafter described and illustrated in the accompanying drawings, in which—

Fig. 1 is a side view of the mechanism of the present invention constituting a part of a wrapping machine;

Fig. 2 is an enlarged fragmentary longitudinal sectional view taken on the line 2—2 of Fig. 3 showing parts of the means for cutting the wrapping material, and parts of the means for advancing the cut material;

Fig. 3 is a plan view of the parts shown in Fig. 2;

Fig. 4 is a vertical transverse sectional view taken on the line 4—4 of Fig. 2 and looking in the direction indicated by the arrows;

Fig. 5 is a fragmentary plan view showing parts of the cutting means of Fig. 2;

Fig. 6 is a fragmentary longitudinal section view taken on the line 6—6 of Fig. 7, showing the stripping means;

Fig. 6a is a sectional view taken on the line 6a—6a of Fig. 6;

Fig. 7 is a plan view of the stripping means shown in Fig. 6;

Fig. 8 is a view similar to Fig. 6 showing the leading end of a wrapper being stripped from the advancing means; and

Fig. 9 is a perspective view of the stripper cam plate.

Figs. 10, 11 and 12 show a modified form of wrapper stripping means.

As before stated, the present mechanism may be used advantageously in a machine for wrapping butter. In such machine the butter which has been cut into substantially square slabs is conveyed along a horizontal path to be printed and cut into patties or chiplets by suitable

2
means adjacent said path, and continues on to suitable wrapping means. The butter printing, cutting and wrapping means are not elements of the present invention.

In Fig. 1 is shown more or less diagrammatically the features of the present invention. It is to be understood certain parts are supported by a suitable stationary frame of which a part is designated 10. A roll 11 of suitable wrapping material, such as stout paper 12, is supported for rotation by suitable bearings on the frame, one of said bearings being designated 13. The material 12 is in the nature of a belt or band and passes from the roll 11 downwardly around a tension roller 14, then upwardly in contact with the roll 11, then over a guide roller 15, then under a feeding roller 16 and between the latter and tension rollers 17, and then is bent around a guide roller 18. The various rollers are supported by suitable fittings and fixtures carried by the frame 10. This frame also supports a table 19 having therein a central longitudinal slot 20. The material 12 passes from the roller 18 over the table 19 substantially horizontally.

In order to advance the material 12 step-by-step or intermittently in conjunction with the feeding of the material by the roller 16, there is provided a plurality of material engaging elements 21 carried by a chain 22 in equally spaced relation to each other. The chain 22 encircles a driving sprocket 23 having intermittent motion, and sprockets 24 and 25, respectively. The sprockets 23, 24 and 25 are mounted on shafts 26, 27 and 28, respectively. The roller 16 is driven by motion transmission means connected with the shaft 27 and the roller 16, said means being shown in dot and dash lines and is designated 29.

Each of the elements 21 is connected with a link of the chain 22, as shown most clearly in Fig. 6a. An element 21 comprises a cross-bar or plate 30 having a reach member 31 on its underside. The member 31 has oppositely extending lateral lugs 32 which are secured by fasteners 33 to corresponding lugs 34 on the particular link of the chain 22. The plate 30 has impaling means thereon consisting of pointed pins or pegs 35 arranged in rows, there being a front row and a back row, and the pins 35 in the front row being somewhat longer than those in the back row. As the chain 22 moves clockwise, viewed in Fig. 1, the elements 21 successively engage the material 12 by impaling it with the pins 35 and advance the material 12 repeatedly a predetermined degree. For the sake of con-

venience and clearness in describing the movement of the material 12, and the cutting of the material into separate pieces constituting individual wrappers, that portion advancing to the cutting means is hereinafter referred to as being the uncut material, whereas the separate pieces or wrappers are referred to as being the cut material.

In order to assist each of the elements 21 to impale the material 12, there is provided a resilient presser 36 secured to a cross-bar 37 whose opposite ends are respectively connected or formed integral with spaced arms 38 of a yoke 39. Pivots 40 extend through the arms 38 and fixed lugs 41 on the table, enabling up and down pivotal movement of the yoke 39. The presser 36 is notched or slotted as at 6 to accommodate the pins 35 as the presser 36 moves downwardly. In moving downwardly the presser 36 presses on the material 12, thereby forcing the pins 35 through the material. This is accomplished during a dwell in the movement of the chain 22 which brings each of the elements 21 in registry with the presser 36. The up and down pivotal movement of the yoke 39, and therefore the presser 36, is effected by means of a rocker 42 which has one end thereof connected with one of the arms 38 by a pivoted link 43. The rocker 42 is operated in timed accord with the operation of the chain 22. After each element 21 is impaled, it draws the uncut material 12 forward a predetermined degree according to the desired length of wrapper wanted. The advancement of the uncut material 12 is the distance between the element 21 at the position A to the element 21 at the position B in Fig. 1.

The uncut material 12 is payed out from the roll 11 and is drawn taut substantially horizontally disposed after leaving the roller 18, by each of the impaled elements 21 in turn. This makes it possible to use the material 12 as a conveyor of the slabs of butter 44 laid on the material 12 one after another in equally spaced relation as shown.

In order to cut or sever the material 12 into separate pieces of the required length to produce individual wrappers, there is provided means comprising three cutting members 45, 46 and 47, respectively, extending transversely with respect to the path of travel of the material 12. The member 45 is mounted for cutting movement with respect to the other members 46 and 47 to cooperate therewith to cut transversely through the material. The member 45 has downwardly diverging cutting edges 48. The member 45 moves in guides 49 rising from the table 19 and is hingedly connected, as at 50, with the cross-bar 51 of the yoke 39. Springs 52 are interposed between the cutting member 45 and the cross-bar 51 to yieldingly hold the member 45 against the guides 49 in a cutting position. The cutting member 45 thus connected and arranged moves up and down with the yoke 39 so that while the pins 35 are being impaled, the material 12 is being cut. It is therefore understood that two of the elements 21 are engaged with the material 12 at the time it is being cut. The cutting member 46 is fixed to the table on the underside at an opening in the table which clears the cutting member 45. The cutting member 47 is supported by a block 53 secured to table on the underside. The member 47 is arranged in alinement with the companion member 46 and is slidable laterally with respect to the path of travel of the reach members 31 in the slot 20. Each of the members

46 and 47 consists of a bar providing a straight edge which coacts with one of the edges 48 of the cutting member 45. The member 47 is slid inwardly to a cutting position and is slid outwardly to an out of the way position so as to clear the members 31. A suitable cam 54 carried by the yoke 31 cooperates with spaced pins 55 on the outer end of the cutting member 47. When the material 12 is being cut the member 47 is in its cutting position with respect to the member 46 so that both of these member will cooperate with the cutting member 45. In Fig. 2 the yoke 39 is shown depressed, thereby causing the cutting member 45 to produce a shearing action in conjunction with the members 46 and 47 cutting the material 12 to sever a piece and at the same time causing the presser 36 to force the leading end of the uncut material to be forced down against the cross-bar 30 impaled by the pins 35 thereon. As the yoke is returned to its up position as shown in Fig. 1, the cam 54 acts on the outermost pin 55 causing the cutting member 47 to move outwardly to clear the slot 20 for the passage of the reach member 31 of the particular impaling element 21 in its forward movement with the chain 22. The next preceding element 21 advances the cut piece or wrapper with a slab of butter 44. Each element 21 advances its wrapper and slab 44 to a transfer point from which the wrapper and its slab 44 is carried through the wrapping means of the machine. On the way to the transfer point each slab 44 is printed and subsequently cut into patties or chiplets.

At the aforesaid transfer point each wrapper is stripped from the impaling means 35. This is accomplished by a stripper 56 hingedly connected, as at 57, with a cross-bar 58 fixedly secured to the table 19. A coil spring 59 surrounding the hinge pintle has one end bearing on the stripper 56 at the top, and the opposite end bearing on the cross-bar 58 at the underside thereof, as shown in Fig. 7. The spring 59 yieldingly holds the stripper in a down position as shown in Fig. 6. The stripper consists of a plate of spring metal notched, as at 60, to provide a transverse row of spring fingers 61. Each notch 60 accommodates a pair of the pins 35 while the fingers 61 engage the leading edge of each wrapper presented thereto. A row of bevels on the plate or bar 30 constitute cam means 62 which cooperate with the fingers 61, respectively, to lift or disengage the wrapper from the pins 35 on said bar 30, as shown in Fig. 8. Thus, the wrapper is free of the translating element 21 so that the wrapper and its slab 44 may be shifted laterally for the wrapping operation. If desired, one or all of the fingers 61 may have a protuberance 63 to facilitate the wrapper stripping action.

In lieu of the means described above for disengaging or stripping each wrapper from the means 35 at said transfer point, use is made of a stripper 65 on each of the material engaging elements 21, and an obstacle 66 arranged to cooperate with said stripper 65 at the transfer point. The stripper 65 consists of a metal plate having a lateral projection 67 and rows of holes 68 to receive the two rows of pins 35 respectively, projecting upwardly through the plate. The stripper 65 is loosely connected with shouldered studs 69 on the cross bar 30 of the element 21, so that the stripper 65 may be actuated to pivot upwardly to free or strip the wrapper from the pins 35. The obstacle 66 consists of a leaf spring. It is disposed at an angle with its lower end secured

as at 70 to a fixed part 71 on the frame so that the projection 67 will encounter the upper end of the spring as the particular element 21 moves forwardly. This will cause the stripper to swing upwardly from its idle position shown in Fig. 11 to its stripping position shown in Fig. 12, thereby disengaging or stripping the wrapper from the pins 35.

From the foregoing it will be understood there is described a mechanism which supports suitable material 12 for guided movement with a portion disposed horizontally. The material is cut by intermittently operable cutting means into separate pieces to produce individual wrappers. The horizontally disposed portion of the uncut material 12, as well as the produced wrappers, serve as a means for conveying or translating the slabs of butter 44. This enables the use of a single means, namely, the chain 22 and the elements 21, for advancing the uncut wrapping material as well as the wrappers laden with the products to be wrapped.

I claim:

1. In a mechanism of the character described, means to support suitable material for guided movement with a portion thereof disposed horizontally and to be cut into individual wrappers, the uncut horizontally disposed portion to receive at intervals articles to be wrapped, a plurality of spaced driven material engaging elements to successively advance the uncut material step-by-step and each of said elements also serving to advance a wrapper with which it is engaged after a material cutting operation, means to sever the material in advance of each of said elements after a dwell in its movement, and means to free the wrapper from each of said elements as the latter is advanced into a predetermined position.

2. In a mechanism of the character described, a cutter comprising a cutting member having cutting movement, a fixed cutting member, and a laterally movable cutting member arranged in alinement with the fixed cutting member, said first cutting member having cutting movement with respect to the second and third cutting members, means to operate the first cutting member, and means to cause the periodic lateral movement of the third cutting member into and out of a cutting position in timed accord with the operation of the first cutting member.

3. In a mechanism as set forth in claim 2, and in combination, a plurality of spaced driven material engaging elements to advance suitable material to be cut by said cutter, each of said elements in turn enabled to pass the cutter during the time the third cutting member is out of its cutting position.

4. In a mechanism of the character described, an endless driving member having intermittent movement, impaling elements on said driving member in equally spaced relation with respect to each other for the purpose of advancing wrapping material intermittently, cutting means for cutting the wrapping material, a presser for pressing the wrapping material into engagement with said impaling elements in order one after another, and means to operate the cutting means and said presser in timed accord with the operation of said driving member.

5. In a mechanism of the character described, a material engaging element movable in a predetermined path to engage and convey the material, said element having material impaling means, an apertured pivotally mounted plate carried by said element through which said im-

paling means project when the plate is idle and which plate may be actuated in response to the movement of said element to disengage the material from the element at a predetermined point along said path, and means to actuate said plate for the purpose stated.

6. In a mechanism of the character described, a plurality of spaced elements movable in a predetermined path, each of said elements having material impaling means consisting of pins to engage material and convey it along said path, a stripper carried by each of said elements adapted to be actuated in response to the movement of the element to free the material from the impaling means at a predetermined point along said path, and a resilient obstacle to actuate said stripper when the latter encounters the obstacle for the aforesaid purpose.

7. In a mechanism of the character described, means to support suitable material for guided movement to be cut into individual wrappers, a plurality of spaced driven material engaging elements to successively advance the uncut material step-by-step and each of said elements also serving to advance a wrapper with which it is engaged after a material cutting operation, means to impart intermittent movement to said elements for the purposes stated, each of said elements having means for impaling the material, means to sever the material at intervals to produce the individual wrappers, and means for stripping each wrapper from the impaling means engaged therewith as the related element is advanced into a predetermined position.

8. In a mechanism of the character described, means to support suitable material for guided movement to be cut into individual wrappers, a plurality of spaced driven material engaging elements to successively advance the uncut material step-by-step and each of said elements also serving to advance a wrapper with which it is engaged after a material cutting operation, means to impart intermittent movement to said elements for the purposes stated, each of said elements having means for impaling the material, means to sever the material at intervals to produce the individual wrappers, and means which cooperates with each of said elements to press the material in engagement with the impaling means of each of said elements as the element reaches a predetermined position.

9. In a mechanism of the character described, the combination of a plurality of spaced driven material engaging elements to advance endless sheet material to be cut in suitable lengths, a cutter operable to cut the material, as aforesaid, said cutter comprising cooperative cutting members one of which is movable up and down and the other one movable laterally between a cutting position in the path of said material engaging elements and a non-cutting position out of the path of said elements, and means causing the movement of the cutting members in succession.

10. In a mechanism as set forth in claim 9, wherein said last means includes a lever on which the cutting member having the up and down movement is hingedly mounted.

11. In a mechanism as set forth in claim 10, and a cam carried by the lever cooperating with the laterally movable cutting member.

12. In a mechanism of the character described, the combination of a table having a longitudinal slot therein, an endless driving element having intermittent movement below said table, a plurality of material engaging elements arranged on the

driving element in equally spaced relation to each other, each of said material engaging elements comprising a cross-bar, means on the underside of the cross-bar connecting the cross-bar with said driving element so that said means may travel in the slot while the cross-bar travels above the table, means on the cross-bar to engage an endless band of material to advance the material so that it may be cut into separate pieces and to advance one of the pieces.

13. In a mechanism as set forth in claim 12, and cutting means operating in timed accord with the intermittent movement of the material to cut the material to produce the separate pieces.

14. In a mechanism as set forth in claim 12, 15 wherein said means on the cross-bar for engaging the material consists of impaling pins.
